OIL AND GAS PRODUCTION GUN
PERFORATORClarence A. Ricou, Shreveport, La., assignor to
Petroleum Increase Corporation, Carthage,
Tex., a corporation of Texas

Application October 9, 1939, Serial No. 298,726

3 Claims: (Cl. 164—0.5)

My invention relates to oil, gas wells and the like, and includes among its objects and advantages the provision of an improved gun adapted to fire projectiles through the well casing or into the surrounding formation in a plurality of directions and at different elevations to increase the productivity of the well.

In the accompanying drawing:

Figure 1 is an elevational view of a gun in accordance with my invention with certain parts broken away for the sake of clearness.

Figure 2 is an elevational view illustrating the manner in which a series of guns may be connected as a unit for firing projectiles at different elevations, and

Figure 3 is an enlarged sectional view illustrating the structural connection between two guns.

In the embodiment selected to illustrate my invention, the gun includes a cylindrical body 12 provided with a plurality of bores 14, 16, 18 and 20 constituting powder or explosion chambers. Each of the chambers 14 to 20 is provided with a projectile 22, and the projectiles and chambers are identical in construction and operation so that the description of one will apply to all.

Figure 1 illustrates the projectile 22 being provided with a cylindrical body 24 disposed in a bore 26 coaxial with the chamber 14, but of larger diameter to provide a shoulder 28. Between the rear face of the projectile 22 and the shoulder 28 I position a lead plate 30 for sealing purposes. The projectile includes a tapered nose 32. Projectile bore 26 communicates with an enlarged bore 34, and within the latter I position a lead washer 36 having a central opening fitting the taper 32. Adjacent the lead washer 36 I position a copper gasket 40 and adjacent the latter I position an iron washer 42. The gasket and the iron washer are provided with central openings fitting the taper 32, and the projectile 22 is pressed against the lead plate 30 through the medium of a clamp ring 44 threaded into the bore 34. Thus the projectile 22 is effectively secured in position, and the securing means constitutes an effective seal to prevent the entrance of moisture into the powder chamber. Body 12 is recessed at 46 to receive a plate 48 having its outer face lying flush with the adjacent face of the body 12, and the plate may be detachably secured through the medium of screws 50. The entire outer surface of the body 12, including the plates 48 are sprayed with a metallized coating 52 to provide a complete moisture protective seal.

Body 12 is provided with a central bore 54 which establishes communication between all the chambers 14 to 20, in addition to communicating with a powder space 56 at the bottom of a bore 58 in the upper end of the body. Bore 54 also extends through the neck 60 at the lower end of the body 12, and the neck is normally closed by means of a screw cap 62.

Inside the bore 58 I position a collar 64 having threaded connection with the bore and spaced from its bottom to provide the powder or explosion space 56. Collar 64 includes a wall 66 bored for the reception of primer caps 68 adapted to fire the explosion in the space 56 for firing the respective chambers 14 to 20.

Inside the collar 64 I threadedly secure a sleeve 70 having a bore 72 for loosely receiving the head 74 of a firing pin assembly 76. Head 74 includes a taper 78 coacting with a similar taper 80 in the sleeve 70 to hold the firing pin assembly in position against any explosive forces effective thereon. Head 74 includes firing pins 82 adapted to fire the primer caps 68 but normally supported out of firing engagement therewith by reason of a shear pin 84 extending through the shank 86 of the firing pin assembly with the ends of the firing pin supported in bores in the collar 64 and the sleeve 70.

A tube 88 is threaded into the bore 58 and is provided with a threaded neck 90 provided with tubing to facilitate lowering of the gun into the well bore or casing. After lowering of the gun to a predetermined depth, a go-devil may be dropped in the tubing to be guided into the tube 88 for engagement with the firing pin assembly 76. Thus the impact of the go-devil will shear the pin 84 and drive the firing pin assembly in firing engagement with the primer caps 68, thus propelling all the projectiles through the well casing and into the surrounding formation for opening up new avenues for the inflow of fluid.

In some cases it is desirable to fire projectiles into the surrounding formation at considerably spaced altitudes. To this end, the cap 62 may be removed and the neck 60 threadedly connected with a tube 92 through the medium of a coupling 94, see Figure 2. The lower end of the tube 92 is connected with the neck 90 of the sectional gun 96 through the medium of a coupling 98. Gun 96 may be identical with that disclosed in Figure 1, and Figure 3 illustrates the structural connection between the two guns.

With the guns connected in multiple, a go-devil 100 is positioned in the tube 92 and includes 55 a shank 102 receivable in the lower end of the bore

54. A shear pin 106 supports the go-devil 100 in its normally inactive position of Figure 3. Referring to Figure 3, it will be noted that the gun 96 includes a firing pin assembly 108 identical with that disclosed at 76 in Figure 2, with the go-devil 100 aligned with the firing assembly 108. Thus when the gun 12 is fired, the explosive forces effective on the shank 102 will shear the pin 106 so that the go-devil 100 will impinge against the firing assembly 108 to fire the projectiles associated therewith.

Neck 90 of the gun 12 may be connected with a perforated tube 110 through the medium of a coupling 112, with the tube 110 connected with tubing 114 which serves as a guide for the go-devil employed for firing that gun. Discs 116 are welded inside the perforated tube 110 to prevent fluid from entering the gun 12 or rising in the tube 114. Discs 106 are ruptured by the gravity propelled go-devil. Upon rupturing of the discs, particularly the upper disc, fluids will rush into the tube 114 and create a vacuum condition in the surrounding formation, which aids in the production of the well. Accordingly, the gun need not be raised in order to produce, since the perforated tube 110 constitutes an inlet for the tubing 114.

Both guns 10 and 96 are each provided with two primer caps 68 so as to increase the firing odds. Occasionally a primer cap might become defective, but in a gun employing a plurality of firing caps, the firing odds are greatly increased and it is seldom that both primer caps of one gun are defective.

Obviously, any number of guns may be interconnected as a unit, and the spacing of the guns may easily be determined through varying the length of the connecting tube 92.

The explosive forces effective on the projectiles 22 will of course rupture the washers 38, 40 and 42, and the openings in the clamp rings 44 constitute rifle bores for the projectiles. The construction of the gun is such as to permit reloading, and the gun is substantially constructed so as to withstand all necessary explosive forces.

Having thus described certain embodiments of my invention in detail, it is, of course, understood that I do not desire to limit the scope thereof to the exact details set forth except insofar as those details may be defined in the appended claims.

What is claimed is:

1. The combination of a plurality of guns each having a plurality of explosive propelled projectiles and gun bores for the projectiles, said guns being detachably connected, impact responsive means for firing the first gun, and explosive responsive means associated with said one gun and coacting with the other gun for firing the latter.

2. A gun of the type described comprising a metallic body provided with a plurality of gun bores, projectiles in said gun bores, means for firing said projectiles, said body being recessed circumjacent said gun bores, metallic plates having margins lying in said recesses, means for securing said plates to said body, said plates being adapted to be ruptured by their respective projectiles, and a metallic coating sprayed over said body and said plates to provide a moisture seal.

3. A gun of the type described comprising a body having a plurality of gun bores, projectiles in said gun bores, an explosion chamber associated with each projectile, an ignition channel common to all said explosion chambers, a firing means for said ignition channel, said ignition channel and said explosion chambers being provided with explosive material, a second gun having a gun bore and a projectile therein, an explosion chamber associated with said last mentioned projectile, including an ignition channel, said last mentioned explosion chamber and ignition channel being provided with explosive material, a firing means for firing said last mentioned explosive, and means responsive to explosive force in said first mentioned gun and coacting with said last mentioned firing means for actuating the same.

CLARENCE A. RICOU.
